(57) **CLAIM**

The ornamental design for a respirator with face seal multiple flexing region, as shown and described.

DESCRIPTION

FIG. 1 is a front perspective view of a new design for a respirator with face seal multiple flexing region.

FIG. 2 is a front view thereof;

FIG. 3 is a back view thereof;

FIG. 4 is a right view thereof, the left view being a mirror image thereof;

FIG. 5 is a top view thereof; and,

FIG. 6 is a bottom view thereof.

The broken lines in the drawing illustrate portions of the respirator with face seal multiple flexing region which form no part of the claimed design, and any shading is provided to illustrate contour only and is not an indication of texture, gloss, etc.
